UNITED STATES PATENT OFFICE.

ANNIE BALL, OF CHICAGO, ILLINOIS.

DESIGN FOR A GAME-COUNTER.

SPECIFICATION forming part of Design No. 17,249, dated April 12, 1887.

Application filed February 14, 1887. Serial No. 227,618. Term of patent 7 years.

To all whom it may concern:

Be it known that I, ANNIE BALL, a resident of Chicago, in the county of Cook and State of Illinois, have invented and produced a new and original Design for Game Counters or Chips, of which the following is a specification, reference being had to the accompanying drawings, forming part thereof.

Figure 1 of the drawings illustrates a face view of a game counter or chip embodying my new design. Fig. 2 is a view in central cross-section.

The body of the counter or chip A is of circular form. On the faces of this body A, which are otherwise flat, are formed the two depressions or grooves a and a' and the intermediate rib, a'' , of curved outline.

The leading feature of my design consists in the concentric grooves a and a' , with the intermediate rib, a'' , formed in the face of the counter.

What I claim as new, and desire to secure by Letters Patent, is—

The design for a game counter or chip herein shown and described, the same consisting of the circular body A, having the oppositely-placed concentric grooves a and a' and the intermediate rib, a'' , on the obverse and reverse sides.

ANNIE BALL.
